UNITED STATES PATENT OFFICE.

ELLEN W. DECKER, OF NEW YORK, N. Y., ASSIGNOR TO JULIUS KAYSER & CO., OF NEW YORK, N. Y., A CORPORATION OF NEW YORK.

LADY'S UNDERGARMENT.

1,102,014.

Specification of Letters Patent. Patented June 30, 1914.

Application filed January 28, 1914. Serial No. 814,847.

To all whom it may concern:

Be it known that I, ELLEN W. DECKER, a citizen of the United States, and a resident of Mariners Harbor, Staten Island, 5 borough and county of Richmond, city and State of New York, have invented a new and useful Improvement in Ladies' Undergarments, of which the following is a specification.

10 The purpose of this invention is to provide an undergarment for ladies' wear of the class known generically as union suits, *i. e.*, an undergarment combining two or more garments usually worn separately.

15 My invention embodies what may be designated as two parts, which combined serve the purpose of a lady's chemise and lady's drawers or so-called knickers. The garment is made in the general form of a bag closed 20 at the bottom, but open at the top, having arm and neck openings, and also open at the sides of the bottom, for leg openings. All of these openings may be equipped with ornamental finishing of any desired character, 25 such as lace, frillings, and the like.

Referring to the drawings, Figure 1 illustrates an elevation of a garment embodying my invention and viewed from the front; Fig. 2 illustrates the same garment, also 30 viewed from the front, but showing it in the position it assumes when upon the body of the wearer.

In the drawings, 1 represents the body of the garment. It is made of such fabric as 35 desired. It is closed at the bottom, as at 2, after the fashion of a bag, and has a neck opening 3, and arm openings 4, at the top, and leg openings 5, 5, at the sides of the bottom. Draw-strings may be employed about 40 the neck, if preferred, in a manner well known.

The bag-like body part is preferably enlarged somewhat commencing at about the waist line of the garment and extending 45 thence to its bottom, so as to provide more material for the hips and abdomen and seat of the wearer and to produce a petticoat effect.

At the upper end of one or both of the 50 leg openings, I prefer to extend such opening as at 6, and provide a series of buttons 7, or preferably snap fasteners, whereby one or both of the leg openings may be enlarged and closed at will for appropriate adjust-

ment or shifting of position of that part of 55 the garment, as the exigencies of use may require.

In applying the garment, the legs of the wearer are thrust through the respective leg openings from the top. The garment is 60 then pulled upwardly and the arms thrust through the respective arm holes and the garment adjusted about the neck by the draw strings or otherwise.

It will be noted that when the garment is 65 upon the body of the wearer, it will assume the position substantially as shown in Fig. 2, that is to say, the legs will cause the leg openings to assume a diagonal position, the closed bottom of the bag-like body will be 70 loosely gathered in upwardly extending folds between the legs of the wearer, and while the width of the garment will be reduced because of the rotundity of the body of the wearer and will therefore fit snugly about the body 75 in the upper part of the garment and at the sides, yet because of the enlarged lower portion of the body part, sufficient material will be present to hang softly and produce the appearance of a petticoat, while serving 80 the function of a combined chemise and drawers or so-called knickers.

A number of advantages are secured by the construction described. The cost will ordinarily be reduced as compared with the 85 cost of the two garments separately and also because of the construction, no reinforcing material about what becomes the crotch in use will be necessary as is essential in ordinary drawers with crotch formation; 90 the cost of finishing the bottom of a chemise and the top of a pair of knickers is avoided. Also the wear upon the lower part of the garment, owing to friction occasioned by leg movement, is very greatly reduced, all of 95 which taken together, result in a series of economies.

The garment automatically adjusts itself to the body formation of the wearer without any drawing or straining and particularly without any binding at the crotch as is usual in the case of an ordinary union suit, hence marked comfort is secured and all parts of the pelvic region of the wearer are covered by the continuous bag-like garment, thus securing warmth and generally 105 hygienic conditions. The garment has a clinging fit admirably adapted for wear.

with ladies' outergarments now in vogue and combines the function of a chemise and drawers with the appearance of a petticoat.

The details of construction may be changed without departing from the essential of the invention.

I claim:

An undergarment of the class stated comprising a body part having neck and arm openings at its upper end and a continuous closed bag-like bottom, and vertical leg

openings at each side, one at least of said leg openings being extended upwardly toward the waistline and provided with suitable fastening devices.

In testimony whereof I have signed my name to this specification in the presence of two subscribing witnesses.

ELLEN W. DECKER.
